UNITED STATES PATENT OFFICE.

VICTOR E. EDWARDS, OF WORCESTER, MASSACHUSETTS, ASSIGNOR TO
MORGAN CONSTRUCTION COMPANY, OF WORCESTER, MASSACHU-
SETTS, A CORPORATION OF MASSACHUSETTS.

PINION-HOUSING FOR ROLLING-MILLS.

SPECIFICATION forming part of Letters Patent No. 730,205, dated June 2, 1903.

Original application filed December 23, 1898, Serial No. 700,186. Divided and this application filed February 4, 1903. Serial No. 141,818. (No model.)

To all whom it may concern:

Be it known that I, VICTOR E. EDWARDS, a citizen of the United States, residing at Worcester, in the county of Worcester and Commonwealth of Massachusetts, have invented a new and useful Improvement in Pinion-Housings for Rolling-Mills, of which the following is a specification, accompanied by drawings forming a part of the same, in

10 which—

Figure 1 represents a front elevation of a pinion - housing embodying my invention. Fig. 2 is an end view of the pinion-housing. Fig. 3 is a vertical sectional view through the 15 center of the pinion-shaft bearings. Fig. 4 is an end view of the housing with the pinions removed therefrom.

Similar figures of reference refer to similar parts in the different views.

20 This application is a division of my pending application, Serial No. 700,186, for an improvement in rolling-mills, filed December 23, 1898, and it relates to certain improvements in the pinion-housings of rolling-mills 25 by which the bearings of the pinion-shafts may be readily removed from the housing; and it consists in the construction and arrangement of parts, as hereinafter described, and set forth in the annexed claims.

30 Referring to the accompanying drawings, 1 denotes the pinion-housing embodying my invention and containing pinions by which the rolls in the housings 2 and 3 are connected together, the pinion-housing being placed intermediate between the pairs of rolls journaled in the housings 2 and 3. The pinion-housing 1 contains the pinion-shafts 4, 5, and 6, placed one above the other, with the upper and central shafts in alinement with the 35 shafts of the rolls in the housing 2 and with the central and lower pinion-shafts in alinement with the shafts of the rolls in the housing 3. The upper pinion-shaft 4 is geared to the central pinion-shaft 5 by gears 7 7 on the 40 shaft 4, engaging gears 8 8 on the central shaft 5, and the lower pinion-shaft 6 is connected with the central pinion-shaft 5 by a gear 9 on the lower shaft 6, engaging the gear 10 on the central shaft 5.

The pinion-housing 1 consists of a pair of 50 upright posts 11 11, preferably integral with the base 12 and inclosing a vertical slot 13 sufficiently wide to receive the journals of the pinion-shafts. The vertical posts 11 11 are provided on opposite sides of the vertical 55 slot 13 with recesses 14, adapted to receive annular journal-bearings 15. The journal-bearings 15 are provided on their outer ends with ears 16, which overlap the posts 11 and are attached thereto by bolts 17, which pass 60 through slightly-elongated holes in the ears 16 and are screwed into the vertical posts 11. The pinion-housing is stiffened by bolts 18, which connect the upper ends of the vertical posts 11 and are arranged to draw them toward each other, so as to pinch the annular 65 bearings 15 in the recesses 14, and thereby securely hold them from movement. By clamping the annular bearings 15 in the curved recesses 14 I also determine the spacing or distance between the centers of the 70 bearings.

By loosening the tightening-bolts 18 and withdrawing the bolts 17 the annular boxes 75 may be withdrawn from the ends of the pinion-shafts, and by removing the bolts 18 the pinion-shafts 6 may be lifted out of the vertical slots 13.

What I claim as my invention, and desire to secure by Letters Patent, is—

1. The combination of the pinion-housing consisting of two vertical posts forming the opposite sides of the housing, each pair of posts inclosing a vertical slot to receive the journals of a series of pinion-shafts, annular 85 journal-bearings held by said posts, and a series of pinion-shafts journaled in said bearings, said posts having circular recesses inclosing a portion of the peripheries of said annular bearings, substantially as described. 90

2. A pinion-housing comprising posts having vertical slots 13, to receive the journals of a series of pinion-shafts and having recesses 14 in the sides of said slots to receive annular journal-bearings, a series of annular 95 bearings 15, provided with ears 16, bolts 17, by which said ears are connected to the housing and a series of pinion-shafts journaled in

said annular bearings, substantially as described.

3. The combination in a pinion-housing of two vertical posts having a common integral base, and inclosing a vertical slot provided with recesses in the sides of said slot to receive journal-bearings, and tightening-bolts, connecting the tops of said posts, whereby

they are clamped against the journal-bearings held in said recesses, substantially as described.

Dated this 2d day of February, 1903.

VICTOR E. EDWARDS.
